(57) **CLAIM**

The ornamental design for the remote controlled toy car, as shown and described.

DESCRIPTION

FIG. 1 shows a right side view depicting an embodiment of a new design of a remote controlled toy car;

FIG. 2 shows a left side view of the remote controlled toy car of FIG. 1;

FIG. 3 shows a top view of the remote controlled toy car of FIG. 1;

FIG. 4 shows a bottom view of the remote controlled toy car of FIG. 1;

FIG. 5 shows a rear view of the remote controlled toy car of FIG. 1; and,

FIG. 6 shows a front view of the remote controlled toy car of FIG. 1.

The broken lines illustrate portions of the remote controlled toy car that form no part of the claimed design.
